JOHN M. ROHLFING, OF PLAINFIELD, NEW JERSEY, ASSIGNOR TO AMERICAN CAR AND FOUNDRY COMPANY, OF NEW YORK, N. Y., A CORPORATION OF NEW JERSEY

PORTABLE ELECTRIC TOOL

Application filed March 9, 1931. Serial No. 521,286.

This invention relates to portable tools such as drills, reamers or the like in which the motive power is electricity, and one object of the present invention is the provision 5 of a reliable and efficient tool of this character, among the advantages of which is a provision for preventing overloading, this result being accomplished in the present instance by so constructing and arranging the 10 driving connection between the motor and the tool spindle that it may easily, quickly and automatically be rendered inoperative when the bit encounters abnormal resistance with the result that the operation of the tool 15 is stopped.

In portable electric tools of the character described, it frequently happens that the drill or other tool, such as a reamer bit, stalls due to encountering abnormal resistance, thus overloading the motor and sometimes burning out the armature. Tools have 20 been constructed which are adapted to use fuses which blow upon such overloading, but continual replacement of fuses is an annoyance and operators frequently resort to fuses which will not blow except under very extreme conditions, and the use of this type of fuse does not effectually prevent burning out of the armature.

25 There is a further disadvantage usually present in tools of the character described in that when the bit encounters abnormal resistance there is a tendency for the fields, tool housing and handles to rotate around the armature, and if such tendency is resisted by the operators of the tool the armature may be burned out while if the operators cannot resist this tendency the entire tool will rotate and this constitutes a source of danger to the operators. Two men are usually required to handle tools such as described herein and said tools are usually provided with oppositely extending handles, one for each man. These tools are usually provided with a single electric switch under the control of one of the men and during actual operation of the tool the operators insert a tool bit into the tool spindle, and then the switch is thrown and the circuit closed whereby the tool commences to function. After the bit

is inserted into the work, if the resistance to cutting or reaming, as the case may be, is not excessive, rotation of the bit will continue, but if the resistance is excessive there is a tendency, as before mentioned, for the fields, tool housing and handles to rotate relative to the bit around the armature of the motor, and frequently, the operators cannot restrain this rotation and cannot throw off the switch quickly enough to prevent rotation of the 60 entire tool and its handles with the result that frequently the operators are injured.

In view of the potential danger present in tools of this character, the present invention contemplates the provision of what may be termed a safe reaming or drilling tool and provides a construction which eliminates the aforesaid danger so that should either operator release the handle either voluntarily or involuntarily due to excessive resistance encountered by the bit, drilling or reaming operation of the tool ceases immediately.

The present invention further provides a new and improved arrangement of gear mechanism for operating the tool spindle.

Another object of this invention is the provision of means interposed between the driving motor and the tool spindle which, during operation of the tool bit, is normally retained in operative driving connection with the tool spindle or the driving medium therefor, but which is automatically shiftable to be disconnected therefrom when occasion demands.

Still another object of this invention is the provision of an automatically operable driving gear for directly driving the tool spindle, which driving gear is shiftable to be freed from its driving connection with the spindle 80 when the tool being driven encounters a resistance such that an operator involuntarily releases the holding handle for the tool.

A further object of the present invention is the provision of a new and improved gear- 95 ing arrangement interposed between the driving motor of a portable tool of the character described and the tool spindle therefor, which arrangement includes a means operable automatically upon application of excess- 100

sive load to the tool spindle for disconnecting the driving connection for said spindle.

This invention further contemplates the provision of means for breaking the electric circuit through the motor, which means is associated with and operable upon automatic disconnection of driving means for the tool spindle; the disconnection occurring when and if an operator releases his grasp upon the tool.

Other objects and advantages of this invention will be apparent from the following description taken in conjunction with the accompanying drawings in which

15 Figure 1 is a side elevation of a portable electric tool adapted for drilling or reaming, certain parts of the figure being taken on the line 1—1, Fig. 2, and other parts of the figure being shown in section to disclose the interior 20 of the gear housing.

Fig. 2 is a top plan view of the tool shown in Fig. 1, with almost all of the motor housing and motor removed to disclose the gear housing and parts therein, certain parts in 25 the view being shown in section.

Fig. 3 is a sectional view through the gear housing taken on the line 3—3, Fig. 2.

Fig. 4 is a sectional view taken on the line 4—4 Fig. 2.

30 Fig. 5 is a view showing the interior of the gear housing, the parts being shown about on the line 5—5 of Fig. 1, the view also showing one of the handles partly in section and showing also fragments of the motor housing, while the upper lever of the gear carrier and the upper bracket member are omitted.

Fig. 6 is a top plan view showing the interior of the gear housing about on the line 6—6 Fig. 1, the view also showing the handles, a portion of the motor housing, and the levers for operating the shiftable gear carrier, and

Fig. 7 is a fragmentary elevation of one of the handles, a part thereof being shown in 45 section.

Referring now more particularly to the drawings, the tool is shown as one adapted for either drilling or reaming and comprises generally a motor housing A to which is secured a gear housing B having a neck C in which the upper end of a tool spindle D is arranged, the latter projecting from the neck and being adapted to hold a drill or reamer bit. Secured to and extending in opposite 55 directions from the outer housing are handles indicated generally at E and more specifically described hereinafter.

The motor housing may be of any preferred or desired construction and the gear housing is attached to its lower edge by means of fasteners 2 which extend through meeting flanges 4. The housing A carries a motor (not shown) having a driving shaft 8 on the end of which the driving pinion 10 is formed.

Formed in the gear housing B is a bearing support 12 receiving ball bearing assembly 14 which is alined with a bearing assembly 16 fitted against an annular shoulder 18 in the neck C and retained in position by a ring member 20 threadedly secured in the end of said neck. The bearing assemblies serve to journal the upper end of tool spindle D and a sleeve 21 surrounds the tool spindle and is interposed between the bearing assemblies as clearly shown in Figure 1. Secured to the upper end of tool spindle D is a pinion 22 retained by a securing nut 23 on the threaded end of said spindle. The pinion 22 is adapted to be driven by the before mentioned motor through the gearing arrangement presently to be described; said gearing arrangement including an intermediate shiftable gear adapted to mesh with and be freed from meshing engagement with the pinion 22 as more clearly pointed out hereinafter.

Arranged in the gear housing B is a main driving shaft 26, to the upper end of which is secured a main driving gear 28 which is constantly in mesh with motor pinion 10 to be driven thereby. As clearly shown in Fig. 3, shaft 26 extends through a guide bracket indicated generally at F which rests upon the lower or bottom wall 32 of the gear housing and which comprises the parallel horizontally arranged arms 34 having alined openings in which are arranged roller bearing assemblies 36 in which the shaft 26 is journaled; the upper bearing assembly 36 resting upon a shoulder 38 extending into the aperture in the upper arm 34 while the lower bearing assembly is supported by the lower wall 32 of the gear housing and is retained in position by a shoulder 40 formed on the lower arm 34 at the opening therein. Intermediate its ends the shaft 26 carries a pinion 42, the purpose of which will be hereinafter described. In the instance shown the shaft 26 is of substantial length and its lower end is arranged in an opening formed in the bottom wall 32 and said opening is surrounded by an internally threaded depending flange 44 through which lubricant may be inserted into the gear housing; said flange being adapted to receive a closure (not shown). In the present instance the pinion 42 is shown as formed integral with the shaft 26, but this is merely by way of example as obviously, within the spirit of this invention, the pinion 42 may be formed independently of the shaft and be connected for rotation therewith in any suitable or desired manner. The bracket F is formed of substantially angle-shaped parts 46 and 48, bolted together as shown at 49, the parts 46 and 48, respectively, defining the U-shaped construction illustrated; the vertical portions 50 of said parts being also connected together in abutting relation by dowels 52 whereby the parts are maintained in proper position

to retain the shaft 26 with its associated gear 28 and pinion 42 in proper relative position. As clearly shown in Fig. 3 the bracket F is connected to the side wall of the gear housing B by means of suitable fasteners such as screws 54 and, if desired, to further retain the bracket in position, parts of the vertical portions 50 thereof may be slotted to receive set screws 51 which will obviously prevent any shifting of the bracket in the gear housing.

The present invention contemplates a new and improved gearing arrangement for driving the tool spindle, the arrangement including a gear carrier G pivotally connected to the driving shaft 26 for horizontal shifting movement in the gear housing, said carrier having a gear which is constantly in mesh with pinion 42 and driven thereby, but which is normally retained out of mesh with pinion 22. The gear is adapted to mesh with pinion 22 upon shifting of carrier G in one direction, and automatically operating means are provided for disengaging the gear from pinion 22, as hereinafter fully described.

As clearly shown in the drawings, particularly Fig. 3, the gear carrier constitutes a gear housing and comprises spaced lever members 56 having enlarged rear end portions 58 and parallel arms 60 between which latter a spindle actuating gear 62 is arranged. The arms 60 are connected by a shaft 64 having a bearing assembly 66 which is arranged within the gear 62 whereby said gear is journaled for free rotation. The gear 62, as clearly shown in the drawings is constantly in mesh with pinion 42 on shaft 26. The levers 56 are substantially identical and are provided with the oppositely arranged lugs 68 through which shaft 64 extends; said lugs serving to support and position the inner race of assembly 66, while the outer race is supported by an annular member 70 secured to the gear 62. The inner race of assembly 66 is keyed to the lower lug 68 as at 63 to restrain said race against rotation. The gear 62 is also provided with an upper shoulder 71 which overlies the upper edge of the outer race of assembly 66 and serves to prevent relative vertical shifting of the outer race as will be obvious.

The rear ends 58 are the pivot ends of the levers and are provided with projecting lugs 72 through which tie rods or connecting bolts 74 extend. The lever members are pivoted to shaft 26 and have bearing assemblies 76 arranged around said shaft; the upper bearing assembly resting upon the upper surface of pinion 42 and supporting a spacer 78 upon which rests the upper assembly 36 in the bracket F. The lower assembly 76 is supported on a spacer member 80 mounted on the lower assembly 36. The ends of lever arms 60 are provided with apertured lugs 84 receiving a pin 86 which connects the levers 56

at this end and which serves as a pivotal connection for a link 88 the purpose of which will be hereinafter more clearly pointed out.

From the above description it is apparent that a gear carrier has been provided which comprises a unit consisting of a housing for gear 62 including spaced lever members 56 connected together by the shaft 64 and by connecting bolts 74 and the pin 86; the carrier being mounted for horizontal pivotal movement relative to the shaft 26, and gear 62 being constantly in meshing relation with pinion 42 and being so arranged as to mesh with and be disengaged from the spindle driving pinion 22, the disengagement occurring upon horizontal shifting or pivotal movement of the gear carrier relative to shaft 26.

The before mentioned link 88 comprises a part of the actuating mechanism for shifting the gear carrier on its pivot, and now referring to Figs. 2, 4, 5 and 6 the link 88 connected at one end to the pin 86 has its other end pivotally connected by means of a pin 90 to one end of a pivot lever 92 consisting of spaced links 94 (see Fig. 4). The lever 92 is pivotally mounted intermediate its ends in a bracket 96 secured to the inner wall of the gear housing by fasteners 98, and has a pin 100 extending through the links 94 and through aligned slots 102 formed in the spaced bracket arms 104. As will be apparent the lever 92 is capable of pivotal movement on pin 100 and also is capable of horizontal shifting in the bracket due to the slots 102. Pivotal movement of lever 92 in one direction is limited by a stop pin 103 extending between the bracket arms 104, as shown clearly in Figs. 5 and 6. Pivotal connected to the opposite end of lever 92 is a connecting link 105, the opposite end of which is secured to a crank 106 fastened to the lower end of a vertically arranged rotatable shaft 108 which is arranged in a guide 110 formed on the gear housing and the upper end of which projects beyond the gear housing and carries crank 112. Connected at one end to the pin 100 is a connection link 114, the other end of which is connected to a crank 116 secured to the lower end of a vertical rotatably mounted shaft 118, the upper end of which projects beyond the gear housing and carries a crank 120. As shown in Fig. 1, the cranks 112 and 120 are arranged adjacent the handles E and are provided with spaced stops 122 and 124 for limiting the movement of the levers 112 and 120 in both directions.

For convenience the handles are designated 126 and 128, respectively; handle 126 containing a switch mechanism which may be conventional. The switch mechanism is controlled by a pivoted switch lever 130 to make and break contact at 132 and said lever is normally retracted by a spring 134.

The crank 112 has its end connected to a

push rod 136 by means of a link 138, and said rod is shiftable in a bearing 140 secured to handle 126. The free end of rod 136 extends through a bearing 141 forming part 5 of a sleeve 142 which is shiftably mounted on handle 126 and normally urged away from the motor housing A by means of a spring 144. The forward end of the bearing 141 is adapted to engage a collar 10 146 on rod 136 when the sleeve 142 is shifted in one direction whereby to shift the rod 136 and turn the link 138 and the crank 112 whereby to rotate the shaft 108. Rotation of the shaft 108, due to shifting of 15 the sleeve 142 and rod 136 will shift the link 105 and lever 92, thereby shifting the carrier G and forcing the gear 62 in a direction toward the pinion 22; this occurring because of the pivotal mounting of the lever 92, the 20 shifting of link 105 serving to pull the link 88. The shifting of the carrier just described will not be sufficient to cause the gear 62 and pinion 22 to mesh. Further shifting of the carrier G is required to cause 25 meshing of gear 62 and pinion 22. This further shifting is a desirable feature because it prevents the actuation of the tool spindle before both operators of the tool are prepared to support the tool in working position. 30 The switch lever 130 may be used to shift the sleeve 142, but ordinarily an operator will shift the sleeve 142 to cause the gear carrier G to shift as above described, prior to actuating the switch lever 130 to the position shown in Fig. 1, where the lever 130 serves to hold the sleeve 142 in its forwardly shifted position. In order to permit swinging of the lever 130 to the position shown in 35 Fig. 1, the free end of rod 136 has a lost motion arrangement in the bearing member 141. The extent of relative movement between the sleeve 142 from its bearing 141 and the rod 136 may be varied by means of an adjusting nut 143. 40 As just described, the carrier G is partially shifted by operation of the sleeve 142. As a matter of fact the carrier is partially shifted by either operator, the total shifting of the carrier causing meshing of the gear 62 45 and pinion 22. To cause further shifting of the carrier G, after it has been partially shifted by operation of sleeve 142, the crank 120 is actuated by a link 148 connected to the lower end of a pin 150 which extends through 50 a sleeve 152 mounted on handle 128, and said pin extends through slots 154 formed in the handle and through a spring block 156 arranged in the handle. Interposed between the spring block 156 and the motor housing 55 A is a spring 158 which normally urges the sleeve 152 away from the motor housing whereby to maintain the gear 62 out of meshing relation with pinion 22. When the sleeve 60 152 is actuated against the compression of spring 158 it will be obvious that the link

148 will be shifted thereby actuating crank 120 and shaft 118 to urge link 114 to force lever 92 in the slots 102, thereby pulling or shifting the carrier G on its pivot (shaft 26) 70 and cause meshing of gear 62 and the pinion 22. It will be apparent that sleeves 142 and 152 may be actuated in any sequence. If sleeve 152 is actuated the carrier G will be shifted so as to cause the gear 62 to shift toward pinion 22, but this shifting movement is not sufficient to cause meshing of gear 62 and pinion 22. The sleeve 142 may then be actuated to cause further shifting of carrier G and meshing of gear 62 and pinion 22. The construction described prevents operation of the tool spindle D before both operators are in a position to resist the strain imposed upon them by operation of the tool, as, even if the motor be started, there can be no drive of the tool spindle until each operator shifts the sleeve under his control a distance such that meshing of gear 62 and pinion 22 is accomplished. 85

During operation of this tool, should the bit encounter a resistance so great that the operators cannot resist the tendency of the fields, housing and handles to rotate relative to the bit, release of a handle by either operator will cause an immediate retraction of the sleeve and a consequent unmeshing of gear 62 and pinion 22. For convenience, the sleeve 152 is provided with a latch element 170 pivoted thereto at 172 and provided with a cam surface 174 which is adapted to extend into one of the slots 154. This latch permits the easy retention of the sleeve 152 in its advanced position such as shown in Fig. 1, but should the operator be forced to release handle 128, the spring 158 will cause retraction of sleeve 152 and the latch 170 will be forced out of engagement with the slot 154 because of the cam surface 174. 95

From the above description it will be apparent that should the bit encounter abnormal resistance to an amount such that rotation of the fields, housing and handles cannot be resisted by either or both of the operators, release of either or both handles will instantly cause disengagement of the gear 62 and pinion 22, thereby eliminating danger of injury to the operators and also preventing burning out of the armature of the motor. 110

The drawings disclose one embodiment of the invention, but they are for illustrative purposes only and it is to be understood that the invention is not limited to the specific details shown, as various changes in the form and proportions of the construction may be made within the scope of the appended claims without departing from the 115 spirit of the invention. 120

What is claimed is:

1. In an electric drill or the like, a driving motor, handles, a tool holding spindle, and gearing between said motor and spindle com- 125 130

prising a main shaft having a pinion, a gear constantly meshing with said pinion to be driven thereby, shiftable means supporting said gear adapted to force the latter into 5 driving connection with the spindle when shifted in one direction and to break the driving connection between the gear and spindle when shifted in the opposite direction, independent lever means associated with each 10 of the handles and connected with the gear supporting means and adapted to be actuated to shift the latter, said lever means being relatively so arranged as to necessitate operation of each thereof to establish driving connection between said gear and spindle.

2. In a tool of the character described, a driving motor, a bit holding spindle, and gearing between the motor and spindle including a gear normally retained out of driving 20 connection with the spindle but shiftable to cause driving connection with the spindle to be established, and a plurality of lever means for shifting the gear, each of said means being adapted to shift the gear partially and 25 the movement of all of said means establishing driving connection between the gear and spindle.

3. In a tool of the character described, a driving motor, a bit holding spindle, and 30 gearing between the motor and spindle including a shiftable gear normally retained out of driving relation with the spindle, and means for shifting the gear in both directions to respectively establish and break 35 driving connection with the spindle comprising independently shiftable lever means each adapted to partially shift the gear when moved in one direction, the combined movements of said levers establishing driving connection of said gear and spindle and each thereof being adapted to break the driving connection between the gear and spindle when they are shifted in the opposite direction.

45 4. In a tool of the character described, a driving motor, a main shaft driven by said motor and having a pinion, a bit holding spindle, and means for driving the tool spindle comprising a gear carrier shiftable about 50 the main shaft, a gear supported by the carrier in mesh with the pinion, handles for the tool, lever means connected to the free end of the carrier and operatively associated with the handles for shifting the carrier in one 55 direction to establish driving connection of the gear and spindle, and means operative upon release of either handle by an operator for actuating the lever means to shift the carrier in the opposite direction to disengage 60 the gear from the spindle.

5. In a tool of the character described, a driving motor, a main shaft driven thereby and provided with a driving pinion, a spindle, an idler gear in constant mesh with said 65 pinion and normally retained out of mesh-

ing relation with the spindle, a pivotally mounted shiftable lever for shifting said idler gear, handles for the tool, a connecting link operatively associated with one of said handles for swinging said lever on its pivot, and a second connection link associated with the other handle for shifting said lever.

6. In a tool of the character described, a driving motor, a main shaft driven thereby and provided with a pinion, handles, a tool spindle, an idler gear in mesh with said pinion to be driven thereby, said idler gear being normally retained out of driving connection with the tool spindle, lever means for shifting the idler gear into driving connection with the tool spindle, and means associated with the handles for actuating the lever means in one direction to connect the idler gear and spindle in driving relation, said means being so formed and arranged as to be automatically operable upon release of a handle by an operator to actuate the lever means in the opposite direction to disengage the idler gear from the spindle.

In witness whereof I have hereunto set my hand.

JOHN M. ROHLFING.
